FREQUENCY OR PHASE MODULATION
RECEIVERMurray G. Crosby, Riverhead, N. Y., assignor to
Radio Corporation of America, a corporation
of Delaware

Application May 26, 1937, Serial No. 144,778

11 Claims. (Cl. 250—20)

This invention discloses a type of frequency modulation receiver wherein the usual sloping filters are replaced by filters whose output is proportional to the frequency deviation on one side of the carrier frequency, but is constant for the frequency deviations on the other side of the carrier frequency. By utilizing two such filters of opposite slopes, followed by linear detectors and proper combining circuits, each detector contributes one half of the modulation envelope to the output in a manner similar to class B push-pull amplification.

In the prior art of frequency modulation reception the modulation is usually detected by first converting the frequency deviations of the carrier to amplitude deviations of the carrier and then detecting these amplitude deviations in the normal manner of amplitude modulation detection. This conversion is effected by passing the frequency modulated wave through a circuit whose output varies linearly with the frequency of the input such as the side of a resonance curve or a suitable filter network. Receivers of this type are described in Usselman Patent #1,794,932 issued March 3, 1931; Crosby Patent #2,060,611 issued November 10, 1936; Crosby United States application #25,026 filed June 5, 1935; Crosby United States application #25,231 filed June 6, 1935 now Patent #2,087,429 dated July 20, 1937; and Crosby United States application #114,894, filed Dec. 9, 1936. It is also possible to utilize a time delay network or radio circuit in such a manner as to superimpose a phase deviation on the wave which is proportional to the frequency deviation caused by the signal so that the phase deviation may be detected by means of a phase detector. Receivers of this type are described in Crosby United States application #618,154 filed June 20, 1932; Crosby United States application #616,803 filed June 13, 1932 now Patent #2,065,565 dated December 29, 1936; Crosby United States application #25,026 filed June 5, 1935; and Crosby United States application #25,231 filed June 6, 1935 now Patent #2,087,429 dated July 20, 1937.

In describing my invention in detail and its relation to the prior art, reference will be made to the attached drawings wherein,

Figure 1 shows a diagram of a receiver arranged in accordance with the present invention. In this circuit the converting units or filter circuits, are shown as rectangles and their respective characteristics are shown in the rectangles;

Figure 2 illustrates a modification of the arrangement of Figure 1. In Figure 2, for the sake

of brevity, portions of the complete receiver as illustrated in Figure 1, have been omitted;

Figures 2a and 2b show modifications of the arrangements of Figures 1 and 2. In these modifications also, for the sake of brevity, the initial stages of the receiver have been omitted;

Figure 3 illustrates the details of additional converting circuits including filters having modified characteristics and their connections to rectifiers to reproduce the signal. The filters shown in detail in Figure 3 may be used in the circuits of Figure 1;

Figures 4 and 5 show graphically the characteristic of the filters of Figure 3;

Figures 6 and 7 illustrate filter circuits which may be used in the rectangles 9' and 18' of Figure 2;

Figure 8 illustrates the characteristic of a converting or filter circuit as known in the prior art and illustrated in some of the applications referred to hereinbefore; while,

Figure 9 illustrates graphically in general the filter characteristic of the present invention.

In all of the receivers of the prior art the converting circuits operate to produce in their output, wave energy the amplitude of which is substantially linearly proportional to input frequency or phase deviation of the carrier wave over the normal radio frequency or intermediate frequency channel of the receiver. That is, the amplitude might have a value of 1 at the carrier frequency, a value of 2 at one edge of the channel and a value equal to zero at the other edge of the channel. In the receiver of this disclosure the prior art is departed from in that the amplitude of the wave at the output of the filter is made zero or at least a substantially constant value from one edge of the channel to the carrier frequency and increases or decreases substantially linearly to a higher or lower value of output from the carrier frequency to the other side of the channel. Graphically, the receivers of the prior art having characteristics as shown in Figure 8, while the receiver of this disclosure, in one of its modifications, has a characteristic as shown in Figure 9 and in all of its modifications follows the teaching of the graph of Figure 9. In both graphs f_1 to f_2 is the channel and f_c is the carrier frequency.

In Figure 8 if the carrier frequency swings in either direction from the mean carrier frequency, there results substantially linear changes in amplitude of the output energy. In accordance with this invention as the carrier frequency decreases (see Figure 9) the output is substantially constant whereas when the carrier frequency increases

the output varies substantially linearly with change in frequency. While Figure 9 illustrates the general principles of the present invention by illustrating one modification thereof various other filter characteristics which are modifications of the arrangement of Figure 9 may be used and some of these have been described herein-after.

In order to receive both halves, e. g., the carrier and both sidebands of the phase or frequency modulated wave, two filters are employed as is shown in Figure 1. The receiver of Figure 1 may be of the radio frequency type or may be as illustrated, of the heterodyne type. In the latter case, the receiver comprises any energy intercepting device such as an aerial 1, a radio frequency amplifier 2, a heterodyne detector comprising an oscillator and a first detector 3, an intermediate frequency amplifier and band pass filter 4, and in addition, an amplitude limiting device 5. The elements 1 to 4 inclusive are so well known in the prior art, such as for example the cases referred to hereinbefore, that they need no illustration here. The limiter 5 may be of the over-loaded tube type or of the automatic volume control type. The limiter 5 per se has been described in the applications referred to hereinbefore and needs no detailed description at this point. The output of the amplitude limiter 5 passes through the primary winding of a transformer 6, the secondary winding of which connects the control grids 30 and 32 of tubes 7 and 8 in parallel so that these tubes are excited in phase by limited energy appearing in 6. Coupling tubes 7 and 8 have their anodes and cathodes connected as shown, to the inputs of two filter or converting circuits included in units 9 and 10. Filters 9 and 10 in the coupling tube plate circuits have opposite slopes with substantially zero output at the carrier frequency as is shown in the graphs in the rectangles 9 and 10 representing filters with characteristics as shown by the said graphs. The outputs of the two filters are fed to the anodes and cathodes of linear diode detectors 11 and 12. Rectification of the modulated waves in 11 and 12 produce currents of varying intensity therein which, in turn, produce potential drops across resistors 34 and 36 which vary substantially in accordance with the modulations in amplitude of the wave in the outputs of 9 and 10. These potential variations are impressed by coupling condensers and resistors 38 and 39 on the control grids of amplifier tubes 13 and 14 and from the anodes of said tubes on the primary windings of a transformer 16, the secondary of which may be connected with any utilization circuit connected with jack 17. The switch 15 permits the anodes of tubes 13 and 14 to be connected in push-pull or in push-push relation.

As the frequency of the limited intermediate frequency wave in the output of 5 deviates with modulation to a frequency higher than the intermediate frequency carrier frequency the output of filter 9 changes substantially linearly with changes in frequency whereas the output of filter 10 remains substantially constant. Consequently diode detector 11 will reproduce that particular half cycle of the modulating or signal wave. When the frequency deviates in the opposite direction filter 10 produces a changing output which is detected by diode detector 12 while the output of filter 9 now remains substantially constant. By means of the push-pull connection of switch 15 with the primary winding

of transformer 16, the two halves of the modulated wave are combined in proper phase so that the full wave of the modulation is received in a manner similar to Class B amplification.

The filters in 9 and 10 may take any form. 5 Preferably these filters are as illustrated at 45 and 46 in Figure 3 and produce characteristics as shown in Figures 4 and 5. These filters each comprise series parallel tuned reactances LC and LC₁ and LC₂ and LC₃ and shunting reactances C₁L and LC₄ and C₁L₁ and LC₅. The terminals of each network is shunted by resistances 43 and 48 and 44 and 47 as shown. These filters are standard band-elimination filters. They would normally be used to eliminate the range of 15 frequencies between F_c and F₂ of Figure 4, or between F₂ and F_c of Figure 5. The carrier is tuned to one edge of the band elimination range so that the frequency modulation swings the frequency into the band elimination range on one 20 side of the carrier and out of the band elimination range on the other side of the carrier frequency. The filters are of a standard design taken from the book "Transmission Networks and Wave Filters," by T. E. Shea. 25

Figure 2 shows an arrangement wherein output at the carrier frequency (of intermediate frequency here) is substantially maximum and frequency or phase deviations produce a decrease in the filter outputs instead of an increase. 30 In rectangle 9' the filter has a characteristic such that as the frequency increases from the carrier frequency the amplitude at the output decreases substantially in proportion to increases in frequency, whereas as the frequency decreases 35 from the carrier frequency the output of filter 9' remains substantially constant at a value substantially equal to maximum output. In filter 10' the reverse operation takes place on change of frequency from carrier frequency. The circuit of Figure 2 is otherwise similar to that shown 40 in Figure 1. In Figure 2 the circuit elements, prior to the outputs of coupling tubes 7 and 8 have been omitted, while the circuits following the outputs of the filters are the same as in 45 Figure 1 and need no further description here.

Figure 6 shows a standard low-pass filter which may be used in the rectangle of 9' of Figure 2. The standard high-pass filter of Figure 7 may be used in rectangle 10'. These filters may be designed so that their cut-off frequencies occurred 50 at the carrier frequency and their frequency of maximum attenuation occurred at the frequency f₂ in the case of the low-pass filter of 9' or f₁ in the case of the high-pass filter of rectangle 10'. Thus, as the frequency is modulated, it is either modulated into the pass band of the filter or towards the frequency of maximum attenuation and minimum output. This receiver operates quite similar to the one of Figure 1 except that the half 55 wave of audio voltage produced by each detector is due to a decrease in the energy applied to the detector instead of an increase as in the receiver of Figure 1.

The receiver of Figure 2 also enables the reception of amplitude modulation by using the push-push connection of switch 15 and switching out the limiter 5 preceding the coupling tubes. In the receiver of Figure 1 the carrier is substantially of zero amplitude so that the amplitude 70 modulation cannot be received. This feature becomes an advantage in the receiver 1 in that there is a tendency to reject amplitude modulation noises. In the receiver of Figure 2 the carrier is substantially of maximum amplitude 75

whereas the side frequencies are either of constant amplitude or decrease with frequency.

Various combinations of the filters of Figures 1 and 2 may be utilized to produce advantages with regard to noise and interference elimination as well as characteristic improvement. For instance, filters 9' and 10 may be utilized with the push-push connection of switch 15. This arrangement or modification may be as illustrated in Figure 2a. Also filters 10' and 9 may be used with the push-push connection for the anodes of tubes 13 and 14. This modification has been illustrated in Figure 2b.

When receivers of Figures 2a and 2b use a combination of a low-pass filter and a band-elimination filter or the combination of a high-pass filter and a band-elimination filter they have as an advantage the fact that interference on one side of the carrier frequency is reduced. In the case of Figure 2a, the filter of 9' has an output which decreases towards zero as the frequency f_2 is approached. Consequently, the closer the interference is to the frequency f_2 , the more will it be eliminated by this filter. The other filter of rectangle 10 has zero or very low output in the total range between the carrier frequency and f_2 . Thus, both filters cooperate to reduce interference on one side of the carrier frequency. If it happens that the interference is on the other side of the carrier frequency, the high-frequency oscillator of the superheterodyne receiver may be tuned to the other side of the signal. This will heterodyne the interference to the other side of the intermediate frequency carrier frequency. Another alternative would be to use the receiver of Figure 2b which discriminates against the interference for the range between f_1 and the carrier frequency.

The detailed operation of the receiver of Figure 2a is as follows: As the carrier is modulated towards the frequency f_1 , the output of the filter of the rectangle 9' will remain unchanged and there will be no amplitude change to be detected by the detector 11. On the other hand, the output of the filter of rectangle 10 changes towards a higher level in linear accordance with the frequency deviation. This amplitude change will be detected by detector 12 so that an output is produced which is in linear accordance with the signalling potentials. Thus, detector 12 furnishes the half wave of the signalling wave which deviates the frequency from f_c to f_1 . When the frequency is deviated towards f_2 , the output of the filter of 9' changes and detector 11 furnishes that half wave of energy. Hence first one detector and then the other operates to furnish the opposite halves of the signalling wave in the same manner that class B audio amplification operates. Since the detector for filter 9' produces an output due to a reduction of the amplitude of the energy fed to the detector, and the detector of filter 10 produces its half wave due to an increase of the energy fed to the detector, the two detector outputs are already of the required opposite phase to make them add up as a full wave. Consequently the push-push or parallel connection of the switch 15 may be used.

The operation of the receiver of Figure 2b is the same as the operation of the receiver of Figure 2a except that the filters are arranged so that the interference elimination takes place for frequencies on the other side of the carrier frequency. In all other respects the operation may be the same.

The circuit of Figure 3 shows a more specific

embodiment of the demodulator of this disclosure. In this modification the units 4 to 5 inclusive of the system have been omitted. The input electrodes of coupling tubes 40 and 42 are shown as being capacitively coupled to the output of the limiter 5. It will be understood that these tubes 40 and 42 correspond to coupling tubes 7 and 8 of Figure 1 and the circuits are interchangeable. Here, as in the prior modifications, the control grids of tubes 40 and 42 are connected in parallel to be energized in phase by the limited phase or frequency modulated wave energy. The anodes of tubes 40 and 42 are connected together as shown by way of impedances 43 and 44 and are coupled to the control grids of tubes 49 and 50 by way of filter circuits 45 and 46 respectively. Damping resistors 47 and 48 are connected in shunt to the output of the filter circuits 45 and 46 respectively. The filters 45 and 46 have characteristics as illustrated in Figures 4 and 5 respectively. The tubes 49, 42, 49, and 50 may be considered coupling tubes although they also amplify the wave energy. The wave energy as modified by the filters 45 and 46 appears on the anodes of tubes 49 and 50 and is impressed by way of impedance couplings 51 and 52 respectively, to the input electrodes of diode detectors 53 and 54 respectively. Detectors of any type may be used here. Preferably the detectors are linear in character. The detected energies are fed by way of filters 55 and 56 to the control grids of amplifier tubes 57 and 58. The filters 55 and 56 eliminate the intermediate frequency energy from the audio circuit so that substantially pure audio frequency energy appears in the primary windings of transformer 16.

In the graphs of Figures 4 and 5 illustrating the filter characteristics f_c is again the carrier frequency, f_1 is the lower edge of the channel, and f_2 is the upper edge of the channel. As will be seen by examining said graphs when the carrier increases in frequency in accordance with modulating potentials the output of filter 45 remains substantially constant whereas the output of filter 46 increases substantially linearly as the frequency increases while the output of filter 45 increases substantially linearly as the frequency decreases from carrier frequency whereas the output of filter 46 remains substantially constant as the frequency deviates from carrier frequency.

The frequency deviation or channel width of the receiver of Figure 3 is not limited to twice the signalling channel. If desired, the radio frequency channel, the intermediate frequency channel, and the frequency deviation may be made many times the signal band of frequencies so that an improvement in signal-to-noise ratio may be effected. This is accomplished because the noise combines with the carrier to form a resultant which is modulated in phase and amplitude. The amplitude modulation is limited off or balanced out and only the equivalent frequency modulation of the phase modulation is received. Due to the method in which the carrier and the noise combine, the noise deviates the phase of the resultant by an amount equal to N/C radians (assuming that the strength of the carrier C is great compared to the strength of the noise N). A phase deviation of N/C radians is equal to a frequency deviation of $F_m N/C$ cycles, where F_m is the beat frequency between the noise voltage and the carrier. This beat frequency cannot be higher than the maximum signalling frequency due to the fact that the audio channel cuts off the noise frequencies above the signalling.

- 5 frequencies since it is not arranged to amplify frequencies higher than the range of signalling frequencies. The applied frequency deviation due to the signal is F_d cycles and may be several times the maximum modulation frequency, F_m , say K times greater. The ratio of the frequency deviation of the signal to the frequency deviation of the noise, or in other words the signal-to-noise ratio would then be $F_d/F_mN/C$, or, where 10 $F_d=KF_m$, would be KC/N . Thus, the normal signal-noise ratio, C/N , that would be obtained in amplitude modulation reception is multiplied by the factor K when frequency modulation is used. There is also a further improvement giving a 15 factor of the square-root of three or two, depending on the type of noise, which is due to the fact that the equivalent frequency deviation of the phase deviation of the noise is proportional to the audio frequency of the noise, F_m . This makes the 20 total improvement due to frequency modulation equal to $1.73K$ or $2K$ depending upon whether the noise is fluctuation noise (tube hiss, thermal agitation, etc.) or impulse noise (ignition and most man-made noise) respectively.
- 25 While I have described my invention as being applicable to heterodyne receivers, obviously it may be used equally well with receivers of the tuned radio frequency type. In this case the receiver will comprise a radio frequency amplifier followed 30 by a limiter which is in turn connected with coupling tubes in turn connected with the filter circuits illustrated in this invention. More preferably the transformer 6 of the various modifications illustrated may be tuned to the radio frequency wave transmitted and may be preceded by any desired number of amplifiers and an amplitude limiter.
- 35 Although in describing this receiver particular reference has been made to a frequency modulated wave and frequency modulated wave demodulating methods and means, it is obvious that the same may be adapted to the reception of phase modulation and I contemplate the use of these receivers for phase modulated wave reception.
- 40 In this case, I will add or use an intermediate frequency or audio frequency correction circuit as described in Crosby United States application #124,967, filed February 10, 1937, and in Crosby United States application #618,154 filed June 20, 50 1932 respectively.

I claim:

1. The method of demodulating wave energy modulated in phase or frequency which includes the steps of, separating said wave energy into two 55 portions, utilizing one of said portions to produce potentials which vary in amplitude substantially linearly as the phase or frequency of said wave varies between the mean phase or frequency of said wave energy and one remote side frequency only, utilizing the other of said portions to produce potentials which vary in amplitude substantially linearly as the phase or frequency of said carrier wave varies between the mean phase or frequency of said wave energy and the other 60 remote side frequency only, and combining said produced potentials to reproduce the signal.
2. The method of demodulating wave energy modulated in phase or frequency which includes the steps of, separating said wave energy into two 70 portions, utilizing one of said portions to produce potentials which vary in amplitude substantially linearly as the phase or frequency of said wave energy varies from its mean phase or frequency in one direction and potentials which are of substantially constant amplitude as the phase or frequency 75

5 frequency of said wave varies from its mean phase or frequency in the other direction, utilizing the other of said portions to produce potentials which are substantially constant as the phase or frequency of said wave varies from its mean phase or frequency in said one direction and potentials which vary substantially linearly as the phase or frequency of said wave energy varies from its mean phase and frequency in said other direction, and combining said produced potentials to reproduce the signal.

3. The method of demodulating wave energy resulting from beating wave energy modulated in phase or frequency with local oscillations to produce a new carrier and side frequencies which are 15 characteristic of said modulated wave energy which includes the steps of, separating said new carrier and side frequencies into two portions each of which includes carrier and side frequencies, utilizing one of said portions to produce 20 potentials which vary in amplitude substantially linearly as the phase or frequency of said carrier varies between its mean phase or frequency and one remote side frequency only, utilizing the other of said portions to produce potentials which vary substantially linearly as the phase or frequency of said carrier varies from between mean phase and frequency and the other remote side frequency only, and combining said produced potentials to reproduce the signal.

30 4. The method of demodulating wave energy resulting from beating oscillations with wave energy modulated in phase or frequency to produce a new carrier and side frequencies characteristic of said modulated wave energy which 35 includes the steps of, separating said wave energy resulting from said beating action into two portions each of which includes new carrier and both sidebands, utilizing one of said portions to produce potentials which vary in amplitude substantially 40 linearly as the phase or frequency of said new carrier varies from its mean phase or frequency in one direction and potentials which are of substantially constant amplitude as the phase or frequency of said new carrier varies in the 45 other direction, utilizing the other of said portions to produce potentials which are substantially constant as the phase or frequency of said wave varies from its mean value in said one direction and potentials which vary substantially lin. 50 early as the phase or frequency of said new carrier varies from its mean value in said other direction, and combining said produced potentials to reproduce the signal.

55 5. The method of demodulation wave energy comprising carrier and sidebands resulting from modulating a carrier in phase or frequency which includes the steps of, separating said wave energy into two portions each of which includes carrier and both sidebands, utilizing one of said portions 60 to produce potentials which vary in amplitude substantially linearly as the phase or frequency of said wave increases from the carrier frequency through one sideband frequency range and potentials which are of substantially constant amplitude as the phase or frequency of said wave decreases through the other sideband range, utilizing said other portion to produce potentials which are substantially constant as the phase or frequency of said wave increases from the carrier frequency through said one sideband frequency range and potentials which vary substantially linearly as said carrier decreases in phase or frequency through said other sideband range and 75

combining said produced potentials to reproduce the signal.

6. The method of demodulation wave energy comprising carrier and sidebands resulting from modulating a carrier in phase or frequency which includes the steps of, separating said wave energy into two portions each of which includes carrier and both sidebands, utilizing one of said portions to produce potentials which increase in amplitude substantially linearly as the phase or frequency of said wave increases from the carrier frequency through one sideband frequency range and potentials which are of substantially constant amplitude as the phase or frequency of said wave decreases through the other sideband range, utilizing said other portion to produce potentials which are of substantially zero amplitude as the phase or frequency of said wave increases from the carrier frequency through said one sideband frequency range and potentials which increase in amplitude substantially linearly as said carrier decreases in phase or frequency through said other sideband range and combining said produced potentials to reproduce the signal.
7. The method of demodulation wave energy comprising carrier and sidebands resulting from modulating a carrier in phase or frequency which includes the steps of, separating said wave energy into two portions each of which includes carrier and both sidebands, utilizing one of said portions to produce potentials which decrease in amplitude substantially linearly as the phase or frequency of said wave increases from the carrier frequency through one sideband frequency range and potentials which are of substantially constant amplitude as the phase or frequency of said wave decreases through the other sideband range, utilizing said other portion to produce potentials which are substantially constant as the phase or frequency of said wave increases from the carrier frequency through said one sideband frequency range and potentials which decrease in amplitude substantially linearly as said carrier varies in phase or frequency through said other sideband range and combining said produced potentials to reproduce the signal.
8. The method of demodulating wave energy modulated in phase or frequency and eliminating from the demodulated output components of undesired wave energy of different frequency which includes the steps of, beating said wave energies with local oscillations of a frequency differing from the mean frequency of said modulated wave energy by a selected beat frequency, separating the energy resulting from said beating action into two portions, utilizing one of said portions to produce potential which decreases in amplitude substantially linearly as the phase or frequency of said modulated wave varies from the mean phase or frequency in one direction, utilizing the other of said portions to produce potentials which are substantially zero as the phase or frequency of said wave varies from the mean phase or frequency in said one direction and potentials which vary in amplitude substantially linearly as the phase or frequency of said carrier varies from the mean phase and frequency in said other direction, adjusting the frequency of said local oscillations to that side of the mean frequency of the modulated energy at which the interfering wave

energy produces with the local oscillations a beat note which is said one direction from said carrier, and combining said produced potentials to reproduce the signal.

9. In a system for demodulating wave energy modulated in phase or frequency, a pair of filter circuits each having an input and an output, one of said filter circuits having a characteristic such that wave energy passed thereby has a substantially constant amplitude in the output thereof for all frequencies of one sideband and an output the amplitude of which varies substantially linearly through variations in frequency through the other sideband, a second filter circuit having characteristics which are opposite to the characteristic of said first named filter, means for impressing frequency or phase modulated wave energy on the inputs of said filters and demodulating means connected with the outputs of said filters.

10. In a system for demodulating wave energy modulated in phase or frequency at signal frequency, a pair of electron discharge coupling tubes each having an input electrode and an output electrode, means for impressing phase or frequency modulated wave energy on the input electrodes of said tubes, a pair of electron discharge rectifier tubes each having input and output electrodes, a filter circuit having a characteristic such that the energy in the output thereof varies substantially linearly with variations in frequency in one direction from a selected mean frequency and is substantially constant for variations in frequency in the other direction from said mean frequency, a coupling between the input of said filter circuit and one of said coupling tubes, a coupling between the output of said filter and the input of one of said rectifiers, a second filter having a characteristic such that the output thereof is substantially constant for variations in frequency in one direction from said mean frequency and varies substantially linearly with variations in frequency in the other direction from said mean frequency, a coupling between the input of said last named filter and the output of the other of said coupling tubes, a coupling between the output of said last named filter and the input of the other of said rectifiers, and means for coupling the output of said rectifiers in push-pull or push-push relation.

11. In a system for demodulating wave energy modulated in phase or frequency at signal frequency, a filter circuit having a characteristic such that all frequencies on one side of the carrier frequency are of like intensity and all frequencies on the other side of the carrier frequency are attenuated substantially linearly in accordance with their frequency, a second filter circuit having a characteristic such that all frequencies passed on said one side of the carrier frequency are attenuated substantially linearly in accordance with their frequencies and all frequencies on said other side of said carrier are passed with like intensities, means for impressing wave energy modulated in phase or frequency on the inputs of the said filters, means for rectifying the energy at the outputs of said filters and means for combining the output energies.
